(57) **CLAIM**

The ornamental design for an electronic deadbolt lock, as shown and described.

DESCRIPTION

FIG. 1 is a perspective view of an electronic deadbolt lock showing my new design;

FIG. 2 is another perspective view of the electronic deadbolt lock thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof; and,

FIG. 8 is a bottom view thereof.

The broken lines illustrate portions of the electronic deadbolt lock that form no part of the claimed design.
